UNITED STATES PATENT OFFICE.

NICOLAY KNUDTZON FOUGNER, OF CHRISTIANIA, NORWAY.

BUILDING OR CASTING OF STEEL-CONCRETE SHIPS.

1,294,891.

Specification of Letters Patent.

Patented Feb. 18, 1919.

Application filed September 30, 1918. Serial No. 256,219.

To all whom it may concern:

Be it known that I, NICOLAY KNUDTZON FOUGNER, of Kongens gate 6, Christiania, in the Kingdom of Norway, have invented certain new and useful Improvements in Building or Casting of Steel-Concrete Ships; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The present invention relates to the building or casting of steel concrete ships or more particularly the walls of middle-sized ships, that the ships varying in size from 150-750 tons. Ships of this size generally have walls 20 which are too thin to permit their being cast between ordinary double lathings consisting of wood or metal lath.

According to the present invention the walls of the ship are cast between an outer lathing of metal netting or the like and an inner lathing consisting of horizontal boards and planks guiding in vertical slots in the frame. Hereby it is obtained that the lathing boards may be inserted rapidly during 30 the casting operation, so that the casting may always be effectively controlled from above.

The necessary horizontal and vertical reinforcements are arranged beforehand in the 35 space between metal netting and wood lathing and after the casting operation has been performed the exterior metal netting or lath is provided with a coat of plaster on the outside in the ordinary manner.

40 On the drawing is diagrammatically illustrated a form of the invention.

Figure 1 is a cross section of the wall of a steel concrete vessel and

45 Fig. 2 is a section of the ship wall on the line II—II of Fig. 1.

The exterior lathing forms a permanent part of the ship and is formed in the ordinary

nary manner by the metal lath 1, which is mounted on the several reinforcement irons 2 and frame 3. The inner lathing is formed 50 by horizontal boards 4, which are placed on top of each other in the manner of stop logs in the vertical guides 5 in the frame 3. Said guides 5 of course may also consist of ribs or irons fastened on the frame 3.

55 During the casting operation boards 4 are put in place in the guides 5, so that the level of the grout is always a little below the top-most board 4. The control of the casting may thus take place from above on the inside as well as through the metal lath from the outside. After the casting operation is completed, the boards forming the inner lathing, are removed.

Claims:

1. In the manufacture of middle-sized steel concrete ships and the like casting the ship's walls between an exterior lathing of metal lath or the like which forms a permanent part of the construction, and an inner 70 lathing of horizontal boards placed one upon the other as the casting progresses and adapted to be removed after the casting operation.

2. The method herein described of manufacturing steel concrete ships, consisting in constructing a permanent outer metal lathing of the height of the wall of the ship and an inner lathing of removable boards to be put in place as the casting progresses to form 80 a space therebetween of a width approximately equal to the thickness of the wall of the ship, filling the space between the lathings with concrete, removing the inner lathing, and applying a coating of plaster to the 85 outer lathing.

In testimony that I claim the foregoing as my invention, I have signed my name in presence of two subscribing witnesses.

NICOLAY KNUDTZON FOUGNER.

Witnesses:

C. NORMAN,
C. FABRICIUS HANSEN.
